UNITED STATES PATENT OFFICE.

LEO A. HENTER, OF PHILADELPHIA, PENNSYLVANIA.

ATTACHING CLIP AND COMB.

Application filed September 9, 1925. Serial No. 55,329.

This invention relates to improvements in article attaching clips, and has particular reference with respect to its cooperation upon a comb.

5 The primary object of this invention is the provision of an attaching clip which may be used in novel manner for cooperation with an article to support the article in a pocket, or on the flap of a garment, or in other convenient location.

10 A further object of this invention is the provision of a novel type of attaching clip including improved means for connecting the same to a comb or other article to secure 15 the same in a definite position thereon against liability of accidental relative movement with respect to the article.

15 Other objects and advantages of the invention will be apparent during the course 20 of the following detailed description.

25 In the accompanying drawing, forming a part of this specification, and wherein similar reference characters designate corresponding parts throughout the several views,

30 Figure 1 is a side elevation of the improved clip and comb.

35 Figure 2 is a fragmentary view of the end of the comb adapted to receive the novel clip, showing the novel construction of the end of 30 the comb for receiving the clip.

40 Figure 3 is an enlarged cross sectional view taken longitudinally at the attaching end of the clip and comb.

45 Figure 4 is a fragmentary perspective view of the improved clip.

50 Figure 5 is a transverse section of the clip substantially on the line 5—5 of Figure 3.

55 In the drawing, wherein for the purpose of illustration is shown only a preferred embodiment of the invention, the letter A may generally designate the improved clip, which is adapted for attachment upon a special type of comb B, although the clip may be used on other articles than combs, such as pencils, pens, etc.

60 The improved clip A is preferably of resilient material, preferably metal, and the same includes the resilient clip sleeve 10, to which the attaching prong 11 is yieldably connected, as by an integral connection. The clip sleeve 10 has the prong 11 connected therewith in integral manner at the lower edge 12, and at a point diametrically opposed to the split 14 of the sleeve 10. The sleeve 10 from the prong or tongue 11 is

provided with the arcuate wing portions 16 and 17 extending for the same degree of arcuation from the center of the prong or tongue 11, and of course terminating at their free ends to provide the split or division 14 60 which permits of the relative flexing of the wings 16 and 17. The sleeve is of course preferably circular or cylindrical in formation, and the same is hollow to provide the passageway 18 adapted to receive the shank of a 65 pen, or pencil, or the shank 20 of the article B thereof. It is preferred to make the wings 16 and 17 as light as possible, and to this end the central part of the material thereof is cut away to provide the openings 70 25, the wings thus leaving a substantially rectangular shaped framework defining the shape of the wings 16 and 17. Along the line of the tongue 11, however, the sleeve 18 is provided with an imperforate body, and in 75 this part of the sleeve 10, and in direct alignment with the center line of the tongue 11, an elongated projection or indentation 30 is struck inwardly of the sleeve passageway 18, which cooperates against the shank of the article which is received in the passageway 18, 80 to grip the said article and prevent the rotation of the clip thereon, or its displacement therefrom. This indentation or projection 30 is preferably stamped directly in the 85 metal, as shown in Figure 3, although the same may be cast to provide the projection. The projection is preferably elongated longitudinally of the tongue 11, and as above mentioned in direct alignment with the 90 tongue 11. It is thus positioned diametrically opposed to the split opening 14.

95 The tongue 11 at its connection point with the sleeve 10 may have an outwardly bowed portion 32, and the tongue at its free end may be provided with the conventional ball head 33.

100 Referring to the novel cooperative feature of the comb B, the comb B is provided with a back 35, outwardly at right angles from which the teeth 36 extend, and end pieces 37 are provided upon the back 35. The back is extended at 40 beyond one of the end pieces 37, and at the free end of this back extension 40, the same is provided with 105 the cylindrical shaped shank 20, which at diametrically opposed sides thereof in alignment with the opposite sides of the comb back 35 is provided with recesses 43 and 44 adapted to selectively receive the projection 110

30 of the clip, as is illustrated in Figure 3 of the drawing.

Referring to the assembly of the clip upon the comb shank, as is illustrated in the drawing, the split sleeve 10 is of course slipped over the shank 20 from the top thereof; the shank 20 preferably being smooth at its exterior surface, unencumbered by any projection tending to obstruct the sleeve, 10 and the shank 20 terminates at the extension portion 40 of the back 35 to provide a shoulder 44^a against which the lower edge of the sleeve may abut. The split sleeve 10 is so slipped upon the shank 20 that its projection 30 extending into the passageway 18 will slip into one of the recesses 43 or 44 provided therefor, and in this relation when the projection is so extended into the recess 43 or 44, the attaching tongue 11 lies along 15 a side surface of the back 35 of the comb B, due to the positioning of the indentations or recesses 43 and 44 in alignment with the side surfaces of the back of the comb. Of course, the sleeve wings 16 and 17 resiliently 20 grip the shank 20 in snug engagement, and thus holds the projection in place in its recess. The clip A may be readily detached from the article B, as by pushing upwardly 25 on the shank 20, and in this respect the upper clip of the projection 30 is tapered, as shown at 50 in Figure 3 of the drawing, which engages a tapered upper edge of the recess 43 or 44, to facilitate the clip removal.

Merely by circumferential movement 30 through 180° the projection 30 may be shifted from one recess 43 to the other 44, or vice versa, and the attaching tongue 11 is also shifted from side to side surface of the back of the comb, so that the clip may be positioned in any relative order upon the comb desired to place the teeth of the comb in the desired direction. This is important, since it may be desirable to have the teeth face in a desired direction with respect to 40 the placement of the comb and clip on the garment of a wearer.

Various changes in the shape, size, and arrangement of parts of the comb and clip may be made to the form of invention herein shown and described, without departing from the spirit of the invention or the scope 50 of the claims.

I claim:

1. As an article of manufacture an attaching clip for supporting articles comprising a resilient split sleeve having an attaching tongue extending outwardly from an end thereof and having a passageway therethrough, an elongated projection carried by the sleeve extending into the passageway thereof in aligning relation with said tongue, said projection having the upper end thereof facing away from said tongue tapering toward the inner surface 60 of the sleeve.

2. As an article of manufacture a metal clip for supporting articles comprising a resilient split sleeve portion of substantially cylindrical formation having a passageway therethrough, a tongue yieldably connected integral with the split sleeve portion and extending beyond an end thereof and at a point diametrically opposed from the split end of said sleeve, said split sleeve having a projection extending into the passageway 70 thereof elongated in alignment with the tongue of said clip at a point diametrically opposed to the split of said sleeve.

3. As an article of manufacture a metal clip for supporting articles comprising a resilient split sleeve portion of substantially cylindrical formation having a passageway therethrough, a tongue yieldably connected integral with the split sleeve portion at an end thereof and at a point diametrically opposed from the split end of said sleeve, said split sleeve having a projection extending into the passageway thereof elongated in alignment with the tongue of said clip at a point diametrically opposed to the split of said 80 sleeve, said split sleeve in the portions lying between the split thereof and the attaching prong having openings therethrough.

4. In a combined comb and clip the combination of a comb including a portion having elongated recesses at opposite sides thereof, and a detachable sleeve having a passageway therein adapted to receive the portion of the comb in which said recesses are formed, said sleeve having an elongated projection extending into said passageway for seating in selective manner in any one of the recesses of the comb, and a tongue carried by said sleeve in cooperative clamping 90 relation with said comb.

5. In a combined comb and clip the combination of a comb including a back portion having teeth thereon and an extended shank projecting beyond an end of said back, said shank having an elongated recess therein aligning with the back of said comb, and a clip including a split sleeve portion and an attaching shank, said split sleeve portion having a passageway therein adapted to receive the shank of the comb 100 and said split sleeve portion having a projection extending into the passageway of elongated formation for seating in the recess of said shank.

6. In a combined comb and clip the combination of a comb including a back having teeth carried thereby, said comb at one end thereof having an extension shank provided with oppositely disposed recesses in alignment with the opposite sides of said comb, and a clip including a split sleeve portion having a passageway therein adapted to receive the top shank, said split sleeve portion having a projection extending into the passageway for seating in selective manner 110 120 125 130

- in either of the recesses of said shank, and an attaching tongue carried by said clip in cooperative extending relation along a side of the comb.
- 5 7. In a combined comb and clip the combination of a comb including an end shank having a recess inwardly of a side thereof, a detachable sleeve for said shank having a passageway therein adapted to receive the shank of the comb, said sleeve having a projection extending into said passageway adapted to detachably seat in snug relation in the recess of the shank of said comb to prevent any relative accidental movement 10 of the sleeve upon the shank either rotary or longitudinal movement thereon, and a tongue carried by the sleeve so as to extend into clamping relation with the comb.
- 15 8. In a combined comb and clip the combination of a comb including a back having oppositely disposed sides with teeth extending outwardly from an edge of the back, said back integral therewith and extending beyond the teeth at the end of the back having a substantially cylindrical shaped shank provided with a lateral indentation therein, a detachable split sleeve for the cylindrical shank and having a passageway therethrough and a projection extending 20 into the passageway adapted to seat in the indentation of the comb shank, and a tongue carried by the sleeve in such relation therewith and with respect to the projection of the sleeve that when the said projection seats in the indentation of the comb shank said tongue will lie along a side of the comb back into clamping relation therewith.
- 25 9. As an article of manufacture an attaching clip for supporting articles comprising a split sleeve having a clamping tongue extending outwardly from one end thereof, said sleeve having a passageway therethrough, and an elongated projection carried by the sleeve extending inwardly of 30 the passageway thereof, the same being of greatest depth at its end opposite to the end of the sleeve from which the tongue extends and from there tapering in depth to its opposite end where it merges into the sleeve.
- 35 10. In a combined article and clip the combination of an article having an attaching shank thereon, and a clip comprising a split sleeve for slipping over the attaching shank having a tongue adapted to rest against the article the tongue extending outwardly from one end of the split sleeve, said attaching shank of the article having a shallow elongated recess therein with blunt edges, and the sleeve inwardly thereof having an elongated projection with blunt tapering edges adapted to slidably and detachably enter and be disconnected with the indentation of said shank merely by slipping of the sleeve longitudinally with respect to 40 said shank.
- 45 11. In a combined article and clip the combination of an article having a shank portion thereon provided with an elongated shallow indentation formed with tapering surfaces bluntly merging into the outer surfaces of the shank, and a clip including a split sleeve slidable upon the shank in a frictional engagement therewith having a resilient tongue extending outwardly from one end of the sleeve, said sleeve having an elongated shallow projection extending into the same for seating in said indentation of the shank, said projection having blunt edges tapering into merging relation with the interior of the sleeve whereby the sleeve may 50 be readily slid upon and off the shank to seat the projection in the indentation of the shank merely by relative movement of the split sleeve longitudinally of the shank, said projection being adapted to snugly seat in the indentation of the shank to prevent normal rotational movement and longitudinal movement of the split sleeve with respect to 55 said shank.
